UNITED STATES PATENT OFFICE.

JOHN G. STITES AND FRANK G. YATES, OF EVANSVILLE, INDIANA.

CHART.

No. 911,083.

Specification of Letters Patent.

Patented Feb. 2, 1909.

Application filed November 9, 1905. Serial No. 286,561.

To all whom it may concern:

Be it known that we, JOHN G. STITES and FRANK G. YATES, citizens of the United States, residing in Evansville, in the county 5 of Vanderburg, in the State of Indiana, have invented a new and useful Improvement in a Chart, of which the following is a specification.

Our invention relates to charts and more 10 especially to charts or guide maps of cities in which different sections are plotted and shown upon a plurality of sheets adapted to be bound into pocket book form.

It is common to secure a map within covers, the map or chart being folded when held between the covers and unfolded and spread open when in use. A chart of this kind is inconvenient to handle unless the party using the same has a convenient place 15 upon which to spread out the unfolded chart, and constant folding and unfolding cause the chart to tear along the line of folding. It is also common to plot various sections of a district and bind the said sections in one cover, 20 but this separates the various sections and renders the chart less readily read than a continuous chart upon one sheet of paper.

The object of our invention is to overcome the disadvantages of both of these constructions and to retain the advantages found in both.

Our invention consists of a plurality of charts bound in book form and following each other in such a successive order that 35 when the book is open the separate sections of the district plotted will be shown and the continuation of said districts will also be shown by folding over either of the charts so that it will lap over upon the marginal portion 40 of the other, the reverse side of each chart forming a continuation of the district plotted upon the face side of the other.

In these drawings:—Figure 1 represents a book having a plurality of pages therein and 45 bearing upon each page a map of a certain portion of a city, the book being shown open. Fig. 2 shows the book open and the right-hand page folded longitudinally so that its right-hand margin overlaps and rests upon the right-hand margin of the page upon the left-hand side. Fig. 3 is a transverse section 50 through the book shown in Fig. 2.

In these drawings, A represents a page bearing a chart showing a certain limited district of a city. This chart extends to the

left-hand side of the page A, but a marginal space A' is left upon the right-hand or bound side.

B represents the opposing page having a certain portion of same city plotted thereon, the chart extending to the free edge of the page and a margin being left adjacent the bound edge. To secure the continuation of either of the districts shown upon these pages, it is only necessary to fold the page 60 longitudinally so that its free edge will overlap the margin upon the other page.

In Fig. 2 page B is shown folded longitudinally its free edge B' being blocked in alignment with the chart shown upon page A, and 70 the page B², which is the reverse of page B, carries a chart which alines with and forms a continuation of the district chart upon page A. In the same manner page A is folded so as to overlap the margin on page B, its 75 reverse side would show a continuation of the chart shown on page B.

It will be obvious that the reverse side of page B carries a chart which is a continuation of that shown upon the face of the page 80 A and that if page B was turned entirely over, it would show the district lying upon the right-hand side of the district shown on page A. In order to more readily grasp the relation of these two districts to each other 85 and the manner in which they form a continuation of each other, it is only necessary to bring the free edge portion of page B² into alignment with the marginal portion of page A, and page A and the folded over portion of 90 page B² will be found to make a continuous chart.

It will be obvious that all of the pages charted are arranged with reference to each other so that the reverse of one page forms a 95 continuation of the face of its opposing page.

Having thus fully described our invention, what we claim and desire to secure by Letters-Patent, is:—

A chart consisting of a plurality of sheets 100 bound together and having contiguous sections of country mapped upon alternate pages, each sheet when folded longitudinally upon itself forming a continuation of the map printed upon an adjacent sheet.

JOHN G. STITES.

FRANK G. YATES.
